LEO M. HARVEY, OF LOS ANGELES, CALIFORNIA

GRIPPER FOR BOX-STRAPPING MECHANISM

Application filed October 3, 1928. Serial No. 310,022.

This invention relates to a gripper for resisting tension in a strap, band or wire, for any purpose. While the invention is useful in many connections, in the present specification it is described as employed in mechanism for placing encircling straps or wires on shipping cases, boxes, bales, or any other article.

In the operation of this mechanism, one end of the metal strip or wire is held in a gripper or pair of jaws, and the strap or wire is then passed around the article to be banded, so that portions of the strap or wire overlap each other. At these overlapping portions, jaws operated by the machine place the tie in the wire. Beyond the position of the tie-forming jaws, the strap or wire must be temporarily held in a clutch. As usually constructed, this gripper must be held open by hand while the wire or strap is introduced into the same by a lateral movement. The general object of this invention is to provide means for automatically opening this gripper by the lateral movement of the wire or strap which places it in the gripper. A further object of the invention is to provide such means with means for retaining the wire or strap in the clutch as it closes.

Further objects of the invention will appear hereinafter.

The invention consists of novel parts and combination of parts to be described hereinafter, all of which contribute to produce an efficient gripper for box strapping mechanism.

In the drawings:

Figure 1 is a plan showing box strapping mechanism with certain parts broken away and illustrating an embodiment of this invention.

Figure 2 is a front elevation of the mechanism shown in Figure 1 and further illustrating the clutch and my improvement.

Figure 3 is a front elevation of the gripper and illustrating the wire in position as though in the act of being introduced by a lateral movement into the gripper. This view illustrates how the wire itself operates to open the gripper to permit the introduction of the wire between the gripper jaws.

Figure 4 is an end view of the clutch mech-

anism and contiguous parts and shows the parts illustrated in Figure 3 as though viewed from the right side. This view shows the parts in the same relation in which they are shown in Figure 3, that is to say, with the wire in the act of being moved laterally into the gripper.

Figure 5 is a view similar to Figure 4, but with more parts broken away, and showing the relation of the parts after the wire has passed into the gripper.

Referring to Figures 1 and 2, 1 represents the strap or wire tying mechanism. This mechanism may be of any construction involving the use of parts for producing a tie overlapping portions of box strap or wire. At one side of this mechanism, a gripper 2 is provided which holds one end 3 of a strap or wire which passes across the front of the tie forming mechanism. This gripper 2 may be of any suitable construction. Its parts are capable of assuming an open position to receive the wire 3, and the gripper mechanism includes a spring for closing the gripper. In the present instance, the gripper includes a relatively fixed jaw 4 and a relatively movable jaw 5 that is pivotally mounted on a pivot screw 6 and presents a cam edge 7 to cooperate with the jaw 4 to grip the wire 3. The pivoted jaw 5 is provided with a projecting handle or arm 8. A coil spring 9 attached to this handle and anchored to a fixed bracket 10, pulls the movable jaw 5 in a direction to clamp the wire in position. Heretofore, in placing the wire 3 in position, it has been necessary for the operator to press the handle 8 toward the left to move the jaw 5 into its open position. The wire 3 is then moved laterally by the operator into the space between the jaws 4 and 5, and the lever 8 is then released to permit the spring 9 to close the jaw.

According to my invention, I construct such a gripper in such a way that merely by moving the wire 3 laterally into the gripper, the gripper will be automatically opened to permit the wire to pass into the space between the jaws.

In applying my invention to a gripper having the construction illustrated, I provide the

movable jaw 5 with means projecting into the path of the laterally moving wire 3, so that the wire will swing the movable jaw 5 to its open position. In order to accomplish this, I prefer to provide a cam 11 attached to the movable jaw 5 and preferably in the form of a plate that projects laterally or transversely with respect to the plane in which the jaw 5 swings on its pivot. This plate is formed on its lower side with a cam edge 12 (see Figure 4). When the wire is moved laterally, it engages this cam edge 12 and this rocks the jaw 5 toward the left on its pivot (as viewed in Figure 3), thereby opening the gap between the jaw 5 and the fixed jaw 4.

As the inward movement of the wire 3 progresses, it eventually passes beyond a vertical edge 13 formed on the inner side of the cam. This edge 13 cooperating with the inclined edge 12 of the cam, forms a spur 14 which operates as a retaining dog to engage the outer side of the wire and retain the same, until the gripper closes. (See Figure 5.)

In practice, the operator simply pushes the wire laterally until it passes this dog 14. Until the wire passes this dog 14, the wire continues to rock the movable jaw 5 on its pivot 6, in opening direction, increasing the tension in the spring 9. As soon as the wire passes the dog 14, the spring 9 moves the jaw 5 to its closing position, thereby clamping the wire 3 between the clamping face or edge 7, and the jaw 4.

It is understood that the embodiment of the invention described herein is only one of the many embodiments this invention may take, and I do not wish to be limited in the practice of the invention, nor in the claims, to the particular embodiment set forth.

What I claim is:

1. A gripper capable of assuming an open position to receive a wire or the like when moved laterally into the gripper, having resilient means for closing the gripper, and means in the path of the laterally moving wire actuated by the laterally moving wire, and operating to open the gripper.

2. A gripper capable of assuming an open position to receive a wire or the like when moved laterally into the gripper, having resilient means for closing the gripper, and means in the path of the laterally moving wire for opening the gripper, said last named means having a dog operating to retain the wire in the gripper as the gripper closes.

3. A gripper capable of assuming an open position to receive a wire or the like when moved laterally into the gripper, with a cam having a cam edge in the path of the wire cooperating with the laterally moved wire to open the gripper.

4. A gripper capable of assuming an open position to receive a wire or the like when moved laterally into the gripper, having a cam with a cam edge in the path of the wire,

cooperating with the laterally moved wire to open the gripper, said cam having a dog operating to retain the wire in the gripper while the same is closing.

5. In a gripper for holding a wire or the like, a relatively fixed jaw, a relatively movable jaw to cooperate with the same to grip the wire, and means in the path of the wire actuated by the wire when moved laterally into the gripper for opening the gripper.

6. In a gripper of the kind described for holding a wire or the like, a pair of jaws, a spring for holding the gripper closed, one of said jaws having a cam with its cam edge in the path of a wire moved laterally into the gripper to open the gripper, said cam edge having a retaining dog to engage the side of the wire after it has passed into the gripper.

7. In a gripper for holding a wire or the like, a relatively fixed jaw, a pivotally mounted jaw, a spring for swinging the same toward the fixed jaw, a cam on the pivoted jaw extending laterally from the same with respect to the swinging plane of the pivoted jaw, said cam having a cam edge to cooperate with a laterally moved wire, to open the gripper.

8. In a gripper for holding a wire or the like, a relatively fixed jaw, a pivotally mounted jaw, a spring for swinging the same toward the fixed jaw, a cam on the pivoted jaw extending laterally from the same with respect to the swinging plane of the pivoted jaw, said cam having a cam edge to cooperate with a laterally moved wire, to open the gripper, said cam having a retaining dog formed in its edge for engaging the outside of the wire.

Signed at Los Angeles, California, this 27 day of Sept., 1928.

LEO M. HARVEY.
